United States Patent Office

Des. 186,944
Patented Dec. 29, 1959

186,944

PUSH-BUTTON UNIT

Julian G. Everett, New York, N.Y., assignor to Crane
Co., Chicago, Ill., a corporation of Illinois

Application November 25, 1957, Serial No. 48,663

Term of patent 14 years

(Cl. D26—13)

Fig. 1

Fig. 2

Fig. 3

Fig. 4

Fig. 1 is a front view of a push-button unit embodying my new design;

Fig. 2 is a top plan view thereof;

Fig. 3 is a bottom plan view thereof; and

Fig. 4 is a left side elevational view of the same.

The dominant features of my design reside in those portions shown in full lines in the drawing.

I claim:

The ornamental design for a push-button unit, substantially as shown and described.
